(57) **CLAIM**

The ornamental design for a restroom paper, as shown and described.

DESCRIPTION

FIG. 1 is a front view of a restroom paper showing my new design;

FIG. 2 is a rear view, thereof;

FIG. 3 is a left side view, thereof;

FIG. 4 is a top view, thereof; and,

FIG. 5 is a top, front and side perspective view of the restroom paper of FIG. 1 shown in a position of use.

The two straight broken lines depict perforations which are

parts of the claimed design.

The curved broken line across the restroom paper denotes the boundary of the claim and forms no part thereof. The broken line illustration of a roll in FIG. 5 is environmental subject matter that forms no part of the claimed design.
